UNITED STATES PATENT OFFICE.

JOHN A. RUSSELL, OF RANGELEY, MAINE.

WINDOW-VENTILATOR.

SPECIFICATION forming part of Letters Patent No. 705,303, dated July 22, 1902.

Application filed March 11, 1901. Serial No. 50,550. (No model.)

To all whom it may concern:

Be it known that I, JOHN A. RUSSELL, of Rangeley, in the county of Franklin and State of Maine, have invented certain new and useful Improvements in Window-Ventilators, of which the following is a specification.

This invention has reference to ventilating appliances, whereby fresh air may be admitted in limited quantities to a room without opening the window.

The invention consists in a window-sash ventilator comprising a series of perforations in the frame of a window-sash, a hinged plate or shutter adapted to cover such perforations, and means hereinafter described for locking the plate in its closed and its wide-open positions.

In the accompanying drawings, Figure 1 represents a cross-section of a window-sash, showing in plan the device embodying my invention as applied to the lower bar of the sash, the shutter being closed. Fig. 2 represents a view similar to Fig. 1, except that the shutter is here shown in its wide-open position. Fig. 3 represents an elevation of a portion of a window-sash with my device applied thereto. Fig. 4 represents a section on line 4-4 of Fig. 3. Fig. 5 represents a view similar to Fig. 4, showing the shutter open.

The same reference characters designate the same parts in all the figures.

Referring to the drawings, the bar 1 of the frame of a window-sash is perforated by a series of holes 2, through which a free flow of air may be had from the outer atmosphere into a room. In order to regulate the admission of air, a plate or shutter 3 is provided and is secured to the sash-bar by hinges 4, about which it is adapted to swing freely. The shutter 3 is attached to the sash-bar 1 on its outer side, and on the inner side of the sash-bar is mounted a device for operating and locking the shutter, consisting of a bell-crank lever 6 7, connected with the shutter by a link 5, attached at one end to the lever-arm 6 and at the other by any suitable means to the shutter. The bell-crank lever is mounted over one of the perforations 2, into which one of its arms may project and through which the link 5 extends. This bell-crank lever is preferably constructed of stiff wire or other suitable material and made in a peculiar

form. The arm 6 of the lever, to which the link 5 is connected, is formed as an offset in a substantially straight piece similar to the crank of an engine, having a main bearing on each side of the connecting-rod, the ends 10 and 11 of which constitute trunnions about which the lever turns, and are held in bearings 8 and 9, attached to the sash-bar on either side of one of the holes 2. The other or operating arm 7 is formed of a second piece of material bent into U shape and suitably secured at its ends to the piece 10 11, one end of the piece 7 on each side of the offset 6. If desired, the whole lever may be formed of one piece of suitable form, though the form described is preferable. The arms 6 and 7 are set approximately at right angles to each other, and the fulcrum of the lever, which is formed by the bearings 8 and 9, in which the trunnions 10 and 11 are held, is set at a slight distance from the surface of the sash-bar, so that when the end of the arm 7 rests against the sash-bar the arm 6, projecting from it, makes an angle with sash-bar which is less than a right angle. Thus when the shutter 3 is closed against the outer surface of the sash-bar, as in Fig. 1, the arm 7 rests against the inner surface of the same and the arm 6 is inclined relatively to the line between the fulcrum and the point of attachment of the link 5 to the shutter, so that any force tending to open the shutter acts through the link 5 and has the effect only of forcing the arm 7 tightly against the sash-bar, thus effectually locking the parts. On the other hand, when the shutter is opened to its fullest extent, (see Fig. 2,) the arm 7 rests against the sash-bar on the opposite side of the fulcrum. The connection between the link 5 and lever-arm 6 is again out of alinement with the fulcrum and the point of attachment of the link to the shutter, and forces acting to close the shutter only tend to increase the amount by which this connection is out of line, and so press the arm 7 against the sash-bar. Thus the shutter is locked when most widely open, as well as when shut.

It will be seen that when the arm 7 of the bell-crank lever is moved so as to close and lock the shutter 3 the link 5 passes by the fulcrum of the lever, being permitted so to do by the form of the arm 6, which is shaped, as

before stated, like the cranks of certain forms of engines. This freedom of movement of the link 5 past the fulcrum of the lever is a very important feature of my invention, as without it the shutter could not be locked when closed, as is here done, by the simple relation of the parts, but would need to be provided with additional locking means, and, further, the shutter may be held closed with a force as great as the stiffness of the materials will permit, for in the closed position the arm 6 and link 5 together constitute a toggle-joint, by which great force may be obtained. A lever of any other form would not permit the link 5 to act in the manner described.

In order that a more perfect closure of the shutter 3 may be obtained, the edges of the shutter are bent inward to form a marginal flange or lip 12, the edges only of which come in contact with the outer surface of the sash-bar, the body portion of the shutter being offset from said outer surface, as shown in Fig. 4. The area of contact of the shutter with the sash-bar (the thickness of the material of which the shutter is made by the length of three edges of the same) is thus much less than it would be if the surface of the body portion of the shutter rested directly against the surface of the sash-bar, and so a given force acting to close the shutter exerts a greater pressure per unit of area of contact, and the wind is more effectually excluded. The shutter is also less liable to freeze fast to the sash-bar in cold stormy weather when constructed as described than if allowed to lie flat against the flat outer side of the sash-bar. The flange or lip 12 surrounds the perforated portion of the sash-bar, or, in other words, the outer ends of the perforations in said bar.

Although I have shown the air-admitting means as a series of holes, I do not confine myself to that particular form, but may use apertures of whatever number, size, or shape may seem most desirable, and also the ventilating device need not be applied only to the bottom bar of a window-sash, but may be fitted to the top or side bars as well.

A great advantage that I claim for my device is its simplicity, cheapness, and the ease with which it can be applied. The shutter may be made of sheet metal pressed or bent

into the shape described and provided with a simple hinge. The bell-crank lever and connecting-link may preferably be of stiff wire, which can easily be bent into the required form, and the bearings which constitute the lever-fulcrum may be ordinary screw-eyes.

In applying the device it is only necessary to bore a few holes in the sash-bar, attach the shutter to the outside of the bar, affix the screw-eyes 8 and 9 at proper places on the inside, slip the trunnions 10 and 11 into their bearings, (the shape of the bell-crank lever and the elasticity of the material allow it to be easily done,) and connect the shutter with the lever.

No great accuracy in the length of the link connecting the lever with the shutter is required, for if the link is a trifle short there will be no difficulty in bringing the lever to its closed locking position, as it will yield sufficiently to enable the link to move past the fulcrum and come into locking relation with the lever.

What I claim as new is—

1. In an apparatus of the character specified, having a perforated sash-bar and a shutter hinged to said sash-bar and adapted to cover the perforations in the same, means comprising a bell-crank lever having an arm 6 connected with the shutter by a link and constructed substantially as described to allow the said link to pass the fulcrum of the lever, a fulcrum advanced beyond the surface of the sash-bar, and a U-shaped arm 7 substantially at right angles to the said arm 6 and adapted to bear against the surface of the sash-bar, for operating the shutter and locking the same when closed and when opened to its fullest extent.

2. The combination with a perforated sash-bar, of a shutter hinged to the outer side of the bar and formed to cover the perforated portion thereof, and shutter-operating means comprising a bell-crank lever hinged to the inner side of the sash-bar, and a link connecting one arm of said lever with the shutter.

In testimony whereof I have affixed my signature in presence of two witnesses.

JOHN A. RUSSELL.
